UNITED STATES PATENT OFFICE.

GEORGE A. LEIGHTON, OF SOUTH BOSTON, MASSACHUSETTS, ASSIGNOR TO AMERICAN CAN COMPANY, OF NEW YORK, N. Y., A CORPORATION OF NEW JERSEY.

METHOD OF MAKING CANS.

1,257,502.

Specification of Letters Patent. Patented Feb. 26, 1918.

Application filed April 3, 1916. Serial No. 88,473.

To all whom it may concern:

Be it known that I, GEORGE A. LEIGHTON, a citizen of the United States, residing in South Boston, in the county of Suffolk and State of Massachusetts, have invented a new and useful Improvement in Methods of Making Cans, of which the following is a specification.

This invention relates in general to hermetically sealed containers having a tear-off part, as for example, sardine cans and the like, and as the invention is hereinafter described in connection with a sardine can, it will be manifest that it has a much wider application and can be used effectively and efficiently in containers for numerous other materials.

A principal object of this invention is the provision of a process of making a can for sardines and the like which may be effectively and economically constructed with a double seam at the top, obviating thereby the necessity of closing the filled can with a soldered seam which must be later torn away to provide access.

A further object of the invention is the provision of a process resulting in the provision of a can having a soldered tear-off bottom and a double seamed top wherein the tear-off bottom is cut from the previously drawn can body.

Other objects and advantages of the invention will be apparent as it is better understood from the following description when considered in connection with the accompanying drawing illustrating the steps in the making of a can in accordance with my invention.

On the drawing,

40 Figure 1 is a top plan view of a container body before the bottom of the same has been cut away in accordance with my invention;

Fig. 2 is a section through the same;

45 Fig. 3 is a top plan view after the bottom part has been cut away;

Fig. 4 is a section through the same;

Fig. 5 is a similar view showing the edges about the cut-away bottom bent inwardly 50 slightly;

Fig. 6 is a similar view showing the edges bent in completely to provide a flange upon which the cut-out bottom may be seated and soldered, said section being taken on the line 6—6 of Fig. 7;

Fig. 7 is a bottom plan view showing the bottom placed upon the inturned edges;

Fig. 8 is a central section through the same;

Fig. 9 is an enlarged detail section taken 60 on the line 9—9 of Fig. 7; and

Fig. 10 is a perspective view of the can and showing the key in place.

In accordance with my invention a sardine can body having side and end walls 65 21 and 22 and bottom wall 23 is drawn in the usual manner, an outwardly extending flange 24, later to be formed in a double seam, being provided. The bottom wall is depressed through its central part at 25, 70 the edge of said depression being spaced inwardly an appreciable distance from the adjacent side and end walls except at one corner at 26, where it is spaced in a farther distance. Thereafter the bottom wall is 75 cut away as indicated in Fig. 4 close to the side and end walls to provide a cut-out bottom part 27 and an open body 28. The body 28 is bent inwardly first, as indicated in Fig. 5 at 29, and then as indicated in Fig. 80 6 at 31, to provide finally a flat inwardly extending flange about the opening formed in removing the bottom. The provision of this flange materially reduces the size of opening so that the bottom may be laid in 85 place upon these flanges, as indicated at 32 in Fig. 8. One corner of the vertical wall of the body is pressed inwardly at 33 and the flange 31 extends inwardly almost to the depression 25, the parts being finally so 90 constructed that the depression 25 fits in the space formed within the flange 31. The point indicated at 26 in Fig. 1 of the bottom, rests within the flange 31 at the depression 33, the corner of the bottom at 95 this point forming a tongue 34 adapted for engagement by a key 35, as will be later described. The parts so formed are soldered together to form a frangible seal, the solder 36 being laid upon the flange 31 and the 100 bottom held thereupon to secure it in place. The top 37 is seamed at 38 on the flange 24 at the top, this flange being narrow so that the seam extends up instead of out at the side, the top having a raised hook flange 105 39 for engaging the flange 24.

It will be manifest that this method or process for forming a can through the cutting away of a part of the body and the subsequent securing together of the edges 110

formed in this cutting with a frangible seal, gives a hermetically sealed closed container which may be opened by breaking away the solder. It permits the body to be constructed by the can maker and furnished to the packer who need only fill the cans and then double seam the top in place, being thereby relieved of the use of any solder in closing, particularly if the contents be cooked while the can is open.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:—

1. The herein described method of making cans, the same consisting in drawing a blank of sheet metal to form the bottom and side walls of the can; cutting out said bottom from the side walls; bending in the walls of the body to reduce the cut-out space and form a sealing flange, a portion of the said wall and of the said sealing flange being bent farther inward than the remainder of said bent in portion, placing the cut-out bottom upon the sealing flange with a portion of the bottom projecting beyond the

portion of the wall farthest bent in, to form a tongue for ripping said bottom from the filled and closed can; and soldering the said bottom to the said sealing flange of the body. 35

2. The herein described method of making cans, the same consisting in drawing a blank of sheet metal to form the bottom and side walls of the can and embossing the bottom to form a panel which may be inset within the sealing flange of the body, said panel being further spaced inward from the side walls at one corner; cutting out said bottom from the side walls; bending in the walls of the body to reduce the cut-out space, and form a sealing flange, one corner of the side walls and the corresponding portion of said sealing flange being bent farther inward than the remainder of said bent in portion, placing the cut-out bottom upon the sealing flange with said panel fitted within said flange and with a corner of the bottom projecting beyond the portion of the wall which is farthest bent in, to form a tongue for ripping said bottom from the filled and closed can; and soldering the said bottom to the said sealing flange of the body. 40 45 50
